UNITED STATES PATENT OFFICE.

CHARLES HENRY RICHARDS, OF BALTIMORE, MARYLAND.

HAT REST AND HOLDER.

SPECIFICATION forming part of Letters Patent No. 436,021, dated September 9, 1890.

Application filed February 8, 1890. Serial No. 339,674. (No model.)

To all whom it may concern:

Be it known that I, CHARLES HENRY RICHARDS, a citizen of the United States, residing at Baltimore, in the State of Maryland, have 5 invented certain new and useful Improvements in Hat Rests and Holders; and I do hereby declare the following to be a full, clear, and exact description of the invention, such as will enable others skilled in the art to which 10 it appertains to make and use the same.

My invention relates to a support for hats, bonnets, or other articles of head wearing-apparel, with means for securing same thereon, and has for its object, mainly, the protection 15 of such articles against injury or crushing in course of transportation in a trunk or hatbox or shipment in any box for any other purpose.

By the use of my invention a hat may be 20 placed in a trunk and exposed to very rough handling without the slightest risk. The hat, being held firmly in place in the manner hereinafter described, is prevented from moving about in the compartment—a very desirable result to be attained, especially in case 25 of ladies' hats, oftentimes very expensive and provided with delicate trimmings, flowers, feathers, &c., easily damaged.

The device when not applied to a trunk or 30 box is admirably well adapted to display such articles as those mentioned in a show-window, case, or on a counter.

The invention will be hereinafter described, and particularly pointed out in the claims.

35 In the accompanying drawings, which form part of this specification, Figure 1 represents an end view of a trunk, partly broken away, showing my invention applied and in use; Fig. 2, a perspective view of the device; Fig.

40 3, a front view in a folded position when not in use, and Fig. 4 an enlarged detail view showing the spring-operating mechanism.

Reference being had to the drawings and the letters thereon, A indicates a back board, 45 to which the support is secured by means of screws or rivets a, passing through a strip of sheet metal B, constituting the body portion of the device, and in which are stamped raised portions CD, affording a housing and journal-bearing for the inner ends of the rods E F. The portion C also incases a leaf-spring G 50 for operating upon rod E, as will hereinafter

appear, and both sides of raised portion C are punctured by apertures b, in which the angular end of rod E is supported, thus allowing 55 a vertical movement thereof, as shown by dotted lines in Fig. 2. The angular end of rod E is flattened on one side at c for engagement with the under side of leaf-spring G and elevation of same when the arm E is raised, the 60 result of which is a tendency to hold said rod in a horizontal position and to return it to that position when moved up or down unless it be moved so far that the portion c passes out of contact with the spring G, in which 65 case the arm will remain folded up or down against the back board A. The balance of rod E may be of any configuration, preference, however, being given to an upward curve terminating in a disk H. 70

Rod or frame F is composed of three parts d, e, and f, the first d of which is journaled in the raised portion D in the lower part of the body B, thus allowing the frame a lateral movement either left or right. Part e is at 75 right angles to part d, parallel with the base-board I, and at its outer end is provided a slight downward projection or bend g, intended to rest in a recess J in the base-board I when the device is in use, held thereby the 80 spring of rods d and e. Rod f is perpendicular and terminates in a disk K, somewhat larger than disk H, and directly below same operating below the crown of the hat just as the other disk does above. These disks H 85 and K should be covered with velvet, chamois-skin, or the equivalent to avoid undue wear at points of contact with the hat or bonnet.

The construction of parts being substantially as described, the operation is as follows: For the purposes of illustration we will suppose my invention applied to a compartment in a trunk. It being desired to secure a hat or bonnet thereon in a manner suitable for transportation, arm E is raised to almost a perpendicular position, whereby spring G is elevated by contact with the corner of the flattened surface c in the angular end of arm E until said surface has passed the point of contact 95 with the spring G, when the latter will bear heavily upon the eccentric surface c' and hold arm E in a raised position until a hat or bonnet has been adjusted over disk K at top of 100

rod or standard *f*. The arm *E* may now be lowered until spring *G* again engages the flattened surface *c*, when it will force and hold arm *E*, with disk *H*, down upon the crown of the hat, thus clamping it securely between the soft cushions of disks.

Should it not be desired to use the rest, the space which it occupies in a compartment may readily be made available by folding the rest, 10 as shown in Fig. 3, viz: Rod *E* may be raised. Rods *d* and *e*, being of spring metal, will allow the projection *g* at the outer end of the latter to be lifted out of recess *J*, when the entire frame *F* may be swung to the left or right 15 against the back board *A*. The arm *E* may now be lowered past its horizontal position until it also lies flat against the back board, in which position it is held by spring *G* in the same manner as when in the same relative 20 position above.

Having thus fully described my invention, what I claim is—

1. A hat rest and holder consisting of a disk supported upon a rod of spring metal 25 constituting a standard having at its base a continuation which is secured at its inner end to a back board by a hinge-joint, in combination with a lug or downward projection for engaging a recess in the base-board, substantially as described.

2. A hat rest and holder consisting of a disk supported upon a frame constituting a

standard secured at its inner end to a back board by a hinge-joint and means for locking the frame in operative position, in combination with an upper disk secured to a rod vertically journaled to the back board and a spring for holding the disks normally in contact with each other, substantially as described.

35

3. A hat rest and holder consisting of a disk supported upon a frame constituting a standard and secured at its inner end to a back board by a hinge-joint and means for locking the frame in operative position, in combination with an upper rod journaled to the back board, having also a disk near its outer end and an angular projection at its inner end provided with a flattened surface for bearing against the concave side of a spring, substantially as described.

40

4. In a hat rest and holder, the combination of back and base boards *A* *I*, body portion *B*, having raised parts *C* *D*, covered disks *H* and *K*, rods *E* and *F*, locking device *g*, and flattened surface *c* on angular end of rod *E*, engaging the concave surface of leaf-spring *G*, substantially as described.

45

In testimony whereof I affix my signature in presence of two witnesses.

CHARLES HENRY RICHARDS.
